[57] **CLAIM**

The ornamental design for a T-shirt, as shown and described.

DESCRIPTION

FIG. 1 is a perspective view of a T-shirt showing my new design; the broken lines partially showing a human form being for illustrative purposes only and forming no part of the claimed design;

FIG. 2 is a reduced front elevational view thereof, the shirt front being shown partially open;

FIG. 3 is a rear elevational view of FIG. 2;

FIG. 4 is a top plan view of FIG. 2;

FIG. 5 is a bottom plan view of FIG. 2;

FIG. 6 is a right side elevational view of FIG. 2, the left side being a mirror image thereof;

FIG. 7 is a front elevational view of an alternate embodiment of the design shown in FIG. 1;

FIG. 8 is a rear elevational view of FIG. 7;

FIG. 9 is a top plan view of FIG. 7;

FIG. 10 is a bottom plan view of FIG. 7;

FIG. 11 is a right side elevational view of FIG. 7;

FIG. 12 is a front elevational view of a second embodiment of the design shown in FIG. 1;

FIG. 13 is a rear elevational view of FIG. 12;

FIG. 14 is a top plan view of FIG. 12;

FIG. 15 is a bottom plan view of FIG. 12; and,

FIG. 16 is a right side elevational view of FIG. 12, the left side being a mirror image thereof.
